UNITED STATES PATENT OFFICE

2,204,689

MECHANISM FOR SUPPLYING FASTENINGS

Ernest Moore, Leicester, England, assignor to
 United Shoe Machinery Corporation, Borough
 of Flemington, N. J., a corporation of New
 Jersey

Application January 16, 1939, Serial No. 251,151
 In Great Britain March 18, 1938

6 Claims.

(Cl. 1-6)

This invention relates to mechanisms for supplying fastenings, and more particularly to mechanisms in which the fastenings move downwardly along inclined raceways from the lower ends of which they are separated in succession. The invention is herein illustrated as applied to mechanism of the same general character as disclosed in United States Letters Patent No. 1,002,422, granted on September 5, 1911, on an application of R. F. McFeeley, for supplying tacks to the tack-driving instrumentalities of shoe machines such as pulling-over machines or certain types of lasting machines. It is to be understood, however, that the invention is more generally applicable to mechanisms for supplying fastenings of various kinds and for various purposes.

An object of the invention is to afford better insurance than heretofore, under certain conditions, that fastenings will move downwardly along their raceways at the times when they are required to do so for the proper functioning of the supplying mechanism. A more particular object is to insure that in mechanism for supplying comparatively light-weight tacks such as are sometimes used in shoe machines a proper flow of tacks along the raceways will take place regardless of friction between the tacks and portions of the mechanism. Tack-supplying mechanism of the character disclosed in the above-mentioned Letters Patent includes a cover which is movably mounted over the lower end portions of the raceways and may be raised, if desired, to afford access to the raceways; and for purposes of this invention the construction herein shown comprises means which operates in automatically determined time relation to the usual tack separator at the lower ends of the raceways to lift the cover a short distance and then to release it to cause to drop and jar the raceways. Such jarring of the raceways tends to counteract any tendency for movement of the tacks to be obstructed by their frictional contact with the raceways; and the lifting of the cover, which is very close to the tacks, serves also to relieve any pressure which the cover may have been applying to the heads of any of the tacks. In mechanism of the illustrated type the tack separator moves in one direction to release the rows of tacks and permit them to move downwardly a short distance along the raceways and then moves in the opposite direction to separate and deliver the endmost tacks; and in the construction herein shown the lifting and release of the cover occurs as the separator moves in the direction to release the

rows of tacks, thus contributing to the proper movement of the tacks at the time when that movement normally takes place. For this purpose, as more particularly herein illustrated, a slide on which the separator is mounted carries a pawl which acts on a finger fast on the cover to lift and release the cover near the end of the movement of the slide in one direction and is yieldable upon engagement with the finger to prevent lifting of the cover as the slide moves in the opposite direction.

The novel features of the invention, including various novel details of construction and combinations of parts, will now be more particularly described with reference to the accompanying drawing and thereafter pointed out in the claims.

In the drawing:

Fig. 1 is a perspective front view of a portion of the tack-supplying mechanism to which the invention is herein illustrated as applied, with the parts in their initial positions;

Fig. 2 shows a portion of the mechanism as viewed substantially in the direction of the arrow A on Fig. 1 with the parts in the same positions;

Fig. 3 is a perspective front view of the right-hand end of the tack separator and parts associated therewith, showing the separator just before it completes a movement toward the left; and

Fig. 4 shows a portion of the mechanism in left-hand side elevation, with the parts in the positions which they occupy when the separator is substantially in the position in which it is shown in Fig. 3.

Tack-supplying mechanism of the well-known type illustrated comprises a plurality of inclined raceways 2 to which tacks are delivered by an oscillatory hopper (not shown) and on which the tacks arrange themselves in rows, the term "raceways" being used herein with reference to grooved portions of the structure which support the rows of tacks by their heads and into the grooves of which the shanks of the tacks extend. At the lower ends of the raceways is a separator 4 comprising a plate fastened at its opposite ends to a slide 6 mounted to reciprocate transversely of the raceways and automatically operated in time relation to the movements of the tack hopper. The separator is provided with pointed fingers 8 (Fig. 3) which hold the rows of tacks against downward movement along the raceways until the points of the fingers pass beyond the endmost tacks upon movement of the separator toward the left, whereupon the rows

of tacks are permitted to move downwardly until the endmost tacks are stopped by engagement with shoulders on the separator, as illustrated in Fig. 3. When the separator is thereafter moved toward the right the fingers 8 separate the end tacks from the tacks next in line and deliver them into conduits by which they are conducted to the tack drivers. Mounted over the upper portions of the raceways is a fixed cover 10, and 5 pivotally mounted on pins 12 in this fixed cover is a movable cover 14 for the lower end portions of the raceways which may be swung upwardly to afford access to the raceways. In the construction herein shown the movable cover 14 is pivotally mounted, as sometimes heretofore, with a glass plate 16 extending over the lower end portions of the raceways to enable the operator to observe the condition of the tacks therein without lifting the cover. The normal position of the cover 14 is adjustably determined by screws 18 which are mounted in forwardly projecting lugs thereon and are arranged to rest at their lower ends on plates 20 which are secured to a removable end block 22 and overlap the separator 4 and portions 10 of the lower end of the raceway structure. Preferably the adjustment is such that the glass plate 16 is very close to the heads of the tacks in the raceways so as to prevent the tacks from being displaced in upward directions.

15 30 For purposes of this invention there is secured to the left-hand end of the movable cover 14, as viewed in Fig. 1, a narrow L-shaped strip 24 provided with a finger 26 (Figs. 2 and 4) which projects downwardly to a position in which its lower end is close to a plate 28 fast on the separator slide 6, this finger being so arranged that by pressure on its rear face the cover 14 may be swung upwardly about the pins 12. Pivotally mounted on a stud 30 on the plate 28 is a pawl 32 the forward end of which is beveled and is arranged to engage a beveled rear face 34 on the finger 26 to lift the cover 14 a short distance, as shown in Fig. 4, as the separator is moved toward the left with reference to an observer at 20 the front of the mechanism, the pawl being held at this time by a spring 36 against a pin 38 on the plate 28. As the separator continues its movement toward the left the pawl is carried past the finger 26, thus releasing the cover and permitting it to drop to jar the raceways by the impact of the screws 18 on the plates 20. Such lifting of the cover occurs substantially at the time when the pointed fingers 8 of the separator pass toward the left out of engagement with the 25 endmost tacks in the raceways, thus relieving any pressure which the cover may have been applying to the heads of any of the tacks in the raceways at the time when the rows of tacks are released by the separator to permit them to move 30 downward. The finger 26 is, moreover, so narrow that the cover is released very shortly after the ends of the fingers 8 pass beyond the endmost tacks, so that the jarring of the raceways by the falling of the cover contributes to the proper 35 movement of the tacks along the raceways against any such tendency as there may be for their movement to be obstructed by their frictional contact with the raceways. Satisfactory insurance is thus afforded that the rows of tacks 40 will be properly advanced into positions for the endmost tacks to be separated when the separator is thereafter moved toward the right, even though tacks which are comparatively short and light in weight are used. It will be understood 45 that when the separator receives its movement

toward the right the cover 14 is not disturbed, since the pawl 32 yields upon contact of the finger 26 therewith until it is in position to snap past the finger into contact with the pin 38.

Having described the invention, what I claim as new and desire to secure by Letters Patent of the United States is:

1. In mechanism for supplying fastenings, the combination with a plurality of inclined raceways for fastenings, and means for separating fastenings from the lower ends of said raceways, of a cover movably mounted over the raceways, and means movable relatively to said cover for lifting it and then releasing it to cause it to drop and jar the raceways.

2. In mechanism for supplying fastenings, the combination with a plurality of inclined raceways for fastenings, and a separator movable to separate fastenings from the lower ends of said raceways, of a cover movably mounted over the raceways, and mechanism for lifting said cover and for releasing it to cause it to drop and jar the raceways in automatically determined time relation to the movements of the separator.

3. In mechanism for supplying fastenings, the combination with a plurality of inclined raceways for fastenings, and a separator movable to separate fastenings from the lower ends of said raceways, of a cover movably mounted over the raceways, and mechanism movable with the separator for lifting said cover and for releasing it to cause it to drop and jar the raceways when the separator is in a predetermined position relatively to the fastenings in the raceways.

4. In mechanism for supplying fastenings, the combination with a plurality of inclined raceways for fastenings, and a separator movable in one direction to permit the rows of fastenings to move downwardly along the raceways and in the opposite direction to separate fastenings from the lower ends of the raceways, of a cover movably mounted over the raceways, and mechanism for automatically lifting said cover and for then releasing it to cause it to drop and jar the raceways each time the separator moves in the first-mentioned direction.

5. In mechanism for supplying fastenings, the combination with a plurality of inclined raceways for fastenings, and a separator movable to separate fastenings from the lower ends of said raceways, of a cover movably mounted over the raceways, said cover having a projection thereon, and a member movable with the separator for engaging said projection to lift the cover and for then disengaging the projection to release the cover and cause it to drop and jar the raceways.

6. In mechanism for supplying fastenings, the combination with a plurality of inclined raceways for fastenings, and a separator mounted for reciprocating movements for separating fastenings from the lower ends of said raceways, of a cover movably mounted over the raceways, said cover having a projection thereon, and a pawl movable with the separator for engaging said projection to lift the cover and for then disengaging the projection to release the cover and cause it to drop and jar the raceways as the separator moves in one direction, said pawl being yieldable upon engagement with said projection to prevent disturbing the cover when the separator moves in the opposite direction.

CERTIFICATE OF CORRECTION.

Patent No. 2,204,689.

June 18, 1940.

ERNEST MOORE.

It is hereby certified that error appears in the printed specification of the above numbered patent requiring correction as follows: Page 1, first column, line 40, after the word "cause" insert --it--; page 2, second column, line 40, claim 4, strike out "the" first occurrence; and that the said Letters Patent should be read with this correction therein that the same may conform to the record of the case in the Patent Office.

Signed and sealed this 8th day of October, A. D. 1940.

Henry Van Arsdale,

Acting Commissioner of Patents.
